UNITED STATES PATENT OFFICE.

CLETUS N. ALLERDING, OF MANSFIELD, OHIO, ASSIGNOR TO THE OHIO BRASS COMPANY, OF MANSFIELD, OHIO, A CORPORATION OF NEW JERSEY.

TROLLEY-LINE CLAMP.

1,048,636.

Specification of Letters Patent. Patented Dec. 31, 1912.

Application filed December 7, 1910. Serial No. 596,016.

To all whom it may concern:

Be it known that I, CLETUS N. ALLERDING, a citizen of the United States, residing at Mansfield, in the county of Richland and State of Ohio, have invented certain new and useful Improvements in Trolley-Line Clamps, of which the following is a specification.

This invention relates to trolley line clamps, and has for its primary object to provide an improved device of this character which will be simple, durable, cheap in construction and effective and efficient in operation.

15 A further object is to provide an improved device of this character having means whereby the clamp may be supported for swivel movement, so as to permit perfect alinement with the conductor wire when attached to the hanger or suspension means.

20 A further object is to provide an improved device of this character having means for detachably connecting the parts together and also means for locking them 25 against accidental displacement.

Other and further objects will appear in the specification and be specifically pointed out in the appended claims, reference being had to the accompanying drawings exemplifying the invention, and in which—

Figure 1 is a side elevation of a trolley line clamp constructed in accordance with the principles of the present invention. Fig. 2 is a section on the line II—II, Fig. 1. 35 Fig. 3 is a section similar to that shown in Fig. 2, of a slightly different form of suspension, and with the several parts in the positions they assume previous to being gripped upon trolley wire. Fig. 4 is a top plan view of the clamping members assembled in engagement with a trolley line wire, parts being broken away to show some details of construction. Fig. 5 is a section on the line V—V Fig. 4. Fig. 6 is an inside 40 elevation of one of the clamping members. Fig. 7 is a similar view of the other clamping member.

In the exemplification of the invention shown in the drawings, an insulated hanger having a base flange 2 is rigidly secured to any suitable support 3 by means of stud bolts 4 which pass through the base flange 2. Within the insulator shield 1 is a mass of insulating material 5, in which is embedded a stud 6, 6^a having its lower end

7, 7^a provided with screw threads, as shown in Figs. 2 and 3. A trolley line or conductor 8 is adapted to be engaged by a pair of clamping members 9 and 10, said clamping members being provided with complementary recesses 11 and 12 to adapt said clamping members to receive a swivel head 13 provided on the lower end of a member 14 having a screw socket therein. The swivel head 13 is separated from the upper portion of the member 14 by a contracted neck 15. In order to provide means for forcing the power arms 16 of the clamping members outwardly from each other, so as to clamp the wire or conductor 8 therebetween, an expanding collar or wedge 17 is slidably mounted upon the member 14 and is provided with one or more inwardly projecting lugs 18, which slide in receiving recesses 19 in the member 14, and which recesses open outwardly through the peripheral wall of the member. Thus connected it will be apparent that by rotating the collar or wedge 17 in the proper direction, the member 14 will be adjusted upon the stud 7, 7^a to force the clamping members upwardly. As the movement of the collar 17 longitudinally with respect to the stud 7, 7^a will be arrested by its engagement with the suspension, a further adjustment of the member 14 on the stud in the same direction will cause the collar or wedge to be forced between the power arms 16 to effect a clamping action of the members on the wire 8.

In the present exemplification of the invention, the clamping members are constructed in the form shown in Figs. 6 and 7 respectively. The clamping member as shown in Fig. 6 comprises a clamping jaw 20 and a power arm 16, substantially in the form of a bell-shaped socket section as shown. On opposite sides of the recess 11, this clamping member is provided with a pair of trunnions 21. Adjacent the inner end of each of said trunnions 21 is a laterally projecting lug 22. The other clamping member shown in Fig. 7 comprises a similar clamping jaw 20 and a power arm 16, and on opposite sides of the recess 12 the curved lateral wall of the clamping member is provided with recesses 23, into which the trunnions 21 of the other clamping member are adapted to be inserted. Extending across the recesses or apertures 23 on the conical side of the lateral wall of

the clamping member are curved shields or aprons 24 which provide a pair of trunnion sockets for the reception of the trunnions 21, and the shields are of a size slightly less than the apertures, enabling said clamping members to be pivotally connected and adapting them to be oscillated about their pivotal axes. Each of said recesses or apertures 23 is of such a shape as to leave a lug or shoulder 25 adjacent the recess 12. When the members are assembled, the lugs 22 of one clamping member are adjacently disposed to the lugs 25 of the other clamping member, but are outside of the same. Said clamping members are then adapted to be assembled or separated at will. When it is desired on the other hand to lock the clamping members together and against accidental displacement, the lugs 22 may be bent inwardly into such position that they will be brought within the shoulders 25 when the clamping members are oscillated relatively to each other, and thereby hold the trunnions within the respective sockets. Consequently, the clamping members will be held in such relative position as will prevent them from being disassembled.

What I claim is:

1. In a trolley line clamp, the combination with a pair of clamping members provided with complementary recesses for the reception of a suspension member, one of said clamping members being provided with a curved lateral wall having spaced passages therethrough and a convex shield or apron extending over each passage on the concave side of said lateral wall to form journal sockets, the said shields being of a size less

than the respective passages, the other of said clamping members being provided with journal lugs adapted to be inserted through said passages into said sockets, said curved lateral wall of the one member being provided with recesses opening from said apertures forming shoulders and the trunnions of said other member being provided with lugs projecting into said recesses.

2. In a trolley line clamp, the combination with a pair of clamping members provided with complementary recesses for the reception of a suspension member, one of said clamping members being provided with a curved lateral wall having spaced passages therethrough and a convex shield or apron extending over each passage on the concave side of said lateral wall to form journal sockets, the said shields being of a size less than the respective passages, the other of said clamping members being provided with trunnions adapted to be inserted through said passages into said sockets, said curved lateral wall of the one member being provided with recesses from said apertures forming shoulders, lugs projecting into said recesses, said lugs being capable of being bent into a position locking the clamping members against separation.

In testimony whereof I have signed my name to this specification, in the presence of two subscribing witnesses, on this 30th day of November, A. D. 1910.

CLETUS N. ALLERDING.
